SIGBERT SEEILIG, OF BERLIN, GERMANY

APPARATUS FOR CRACKING OILS

Application filed December 29, 1926, Serial No. 157,828, and in Germany March 25, 1926.

The present invention relates to apparatus for cracking oils and similar fluids.

It is known to crack oils in a continuous process by conducting the same through a vessel which contains molten metals and allowing the oils to ascend through the liquid metal mass.

In order that the cracking may take place in such a manner, that the desired products are obtained it is necessary to accurately maintain certain fixed temperatures, the degree of which depends upon the nature of the products to be produced. Because the cracking takes place at high temperatures it is very difficult in practice to maintain the correct temperatures constantly and accurately. Several arrangements have been proposed for the purpose in question but all arrangements hitherto known operate exclusively mechanically by regulating the flow of the oils or the molten metal bath in a suitable way. Experience has shown, that such devices operate very imperfectly and do not secure an accurate maintenance of the desired temperature.

According to the present invention the above mentioned drawbacks are avoided by arranging an insulating, that is, a cooling medium between the heated wall of the reaction vessel and the interior space of the same in which the decomposition or cracking of the oils takes place. The effect of this intermediate medium is, that the heat from the hot wall will not penetrate to the reaction chamber and consequently the temperature in the said chamber will not be influenced by temperature changes at the wall of the vessel.

The device by means of which the new method is carried into effect consists principally of a spiral, which is arranged in the vessel, coaxially with the same. This spiral consists preferably of a metal tube the cross section of which may be circular, elliptical or of another form and which is exposed towards the steam space. When the apparatus is operating and the heat from the outer wall of the vessel reaches the spiral tube, the medium in the same (for instance steam) will expand and thereby absorb heat. On account of the low conductivity of the said medium the intermediate spiral forms an insulating wall,

which only slowly takes up the temperature of the outer wall and thereby balances the changes of temperature in the same. Any surplus of heat is absorbed by the medium in the spiral and can not penetrate into the interior of the vessel.

According to a further form of the method the spiral tube is evacuated. The vacuum in the tube is an even better heat insulator than gas or steam.

Water vapour, air or another gas may also be conducted through the spiral in order to take up the surplus heat.

Through the open spaces between the windings of the spiral the descending molten metal bath again reaches the wall and is heated anew.

Also oil may be used as cooling medium in the spiral tube.

According to a further feature of the invention the oil mixture may be used as a cooling medium which afterwards is to be treated in the apparatus. When this oil mixture has passed through the spiral tube it is conducted into the reaction chamber in a suitable way.

Two preferred forms of the apparatus by means of which the process may be performed are shown schematically in the accompanying drawing, in which:

Fig. 1 is a vertical sectional view of one form of the apparatus.

Fig. 2 is a top view of the same apparatus with the cover removed.

Fig. 3 is a vertical sectional view of the second constructional form of the apparatus.

The Figs. 4 and 5 show details.

The vessel *a* shown in Figs. 1 and 2 is externally heated in a furnace (not shown). The oils to be treated are conducted into the vessel through the tube *e*, which ends at some distance from the bottom of the vessel. On account of their low specific weight the oils will ascend hastily through the molten metal mass and thereby create an upwardly directed current in the same. The reaction chamber is by means of the spiral tube *c* completely protected against the heat radiating from the wall of the vessel *a*, so that no heat from the said wall can penetrate into the reaction chamber. The entire vessel is suitably filled

with spirals *d* of fine wire, in order to secure a thorough distribution of the oils in the molten bath. The above described measure makes it possible to easily maintain a constant temperature in the reaction chamber. 5 During its upward flow the molten bath is cooled, so that a constant drop of temperature takes place in the reaction space. The surface layer of the molten mass, which has become specifically heavier, sinks down along the wall of the vessel outside of the reaction space, whereby it easily passes outward through the intermediate spaces between the coils of the spiral tube *c*. 10 15 The spiral tube *c* is supported by the carrier member *b*, which may be formed with perforations or the like in order to bring forth a preliminary distribution of the oils introduced at the bottom of the vessel. 20 In the embodiment shown in Figs. 3, 4 and 5, the molten metal bath is confined in the chamber adjacent the inner wall of which is the spiral tube *h*. Oil is admitted to the spiral at end *j* and passes through the spiral *h* issuing therefrom through a distributor *f* and thereafter passes up through the molten metal. Packing material *k*, occupies the space defined by the spiral and assists in securing intimate contact of the oil with the 25 30 molten metal.

Figs. 4 and 5 show the spiral *h* in greater detail, baffles *g* being provided thereon to direct the flow of metal, this being indicated by the arrows.

35 I claim:

1. In an apparatus for cracking oils and the like, a reaction vessel adapted to be externally heated and to contain a charge of molten metal, a continuous spiral tube annularly spaced from the inner walls of said chamber and disposed within said chamber in a position adjacent said walls, said tube being adapted to contain a fluid circulating therethrough to retard the flow of heat from said walls to the interior of the vessel, and means to conduct oil to be treated into said vessel. 40 45 50 55 60 65 70 75 80 85 90 95 100 105 110 115 120 125 130
2. In an apparatus for cracking oils and the like, a reaction vessel adapted to be externally heated and to contain a charge of molten metal, a continuous spiral tube annularly spaced from the inner walls of said chamber and disposed within said chamber in a position adjacent said walls, said tube being adapted to contain oil to be treated, means exterior of said vessel to conduct oil to be treated into the upper end of said tube, a distributor on the lower end of said tube, the lower end of said tube being thereby in communication with the interior of said vessel whereby oil admitted to said tube passes therethrough and, on leaving said tube, comes into contact with the aforementioned molten metal.
3. The apparatus as in claim 2 in which

the spiral tube is provided with baffle members.

In testimony whereof I have signed my name to this specification.
